UNITED STATES PATENT OFFICE.

EDWARD F. MITTENDORF, OF ADDIEVILLE, ILLINOIS.

COMBINED ROAD SCRAPER AND DRAG.

1,243,329.

Specification of Letters Patent.

Patented Oct. 16, 1917.

Application filed March 26, 1917. Serial No. 157,509.

To all whom it may concern:

Be it known that I, EDWARD F. MITTENDORF, a citizen of the United States, residing at Addieville, in the county of Washington and State of Illinois, have invented certain new and useful Improvements in Combined Road Scrapers and Drags, of which the following is a specification.

This invention relates to improvements in road machines, and more particularly to a combined road scraper and drag.

The object of the invention is to provide a simply constructed and efficient machine of this character having peculiarly constructed scraping blades which will operate to loosen and scrape the earth during its passage over the road or other surface.

Another object of the invention is to so construct a machine of this character that the wheels may be set at any desired angle, and two of said wheels at one side of the machine set simultaneously.

Another object of the invention is to so construct the supporting or ground wheels that all possibility of skidding of the machine will be prevented.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:

Figure 1 represents a plan view of a road scraping machine constructed in accordance with this invention, and

Fig. 2 is a transverse section taken on the line 2—2 of Fig. 1.

In the embodiment illustrated, this improved drag comprises a front beam 1 and a rear beam 2 connected by end cross beams 3 and 4 and intermediate cross beams 5 and 6 whereby the machine is braced and strengthened as well as the two beams 1 and 2 connected. Arranged on the front beam 1 are a plurality of scraping blades 7 which are bolted or secured to said beam in any suitable manner, said blades being preferably disposed directly beneath the beam and having their earth working points 8 slightly twisted as shown clearly in Figs. 1 and 2 to dispose them at an oblique angle to the

travel of the machine so that a peculiar cutting and scraping effect will be produced thereby.

This machine is supported on four wheels 9 mounted on angular axles 10, said axles being preferably L-shaped and carried by brackets 11 which project laterally from the beams 1 and 2. These axles are also mounted to turn in apertured lugs or bearings 12 which project upwardly from the end cross bars 3 and 4. These axles 10 are provided at their free ends with bevel gears 13 which are designed to mesh with cooperating bevel gears 14 carried on the ends of rods 15 which extend longitudinally of the machine and are supported in suitable bearings 16 carried by the end cross bars 3 and 4 and bearings 17 carried by the intermediate cross bars 5 and 6. These rods are provided at their inner ends with upstanding levers 18 which are preferably made integral with the rods and by means of which the rods are rotated for setting the wheels 9.

The bearings 17 have segmental racks 19 with which are designed to be engaged spring actuated dogs 20 carried by the levers 18 for locking said levers in adjusted position. These dogs 20 may be released by bell cranks 21 supported on the upper free ends of the levers and connected with the dogs by rods or wires 22. The two levers at the rear of the machine are connected with those at the front by means of rods 23, as is shown clearly in Fig. 2 so that the setting of one lever either at the front or rear will operate to set the corresponding lever and the wheels connected therewith.

A platform 25 is preferably supported by cross bars 5 and 6 for the operator to stand on, and if desired, it may be equipped with a seat.

Draft chains 26 and 27 are connected with opposite ends of the front beam 1 and are made of different lengths to operate as an evener for drawing the machine over the road to be treated, said chains being here shown connected by a link or ring 28, with which a swing-tree or other draft apparatus, not shown, may be connected.

The wheels 9 have their peripheries constructed substantially V-shape in cross section to afford gripping edges 9' as is shown clearly in Fig. 1 and by means of which sidewise movement or skidding of the machine is prevented.

A drag 30 is supported on the rear beam 2

and operates as a leveler for the earth plowed up or scraped by blades 7. This drag 30 is connected with the front beam by means of a rod 24 which operates as a spacer for holding said drag in proper position in relation to the blades.

In the operation of this machine, the parts being in the position shown in Fig. 1, the operator standing on the platform 25 may 10 change the direction of movement of the machine by varying the angle of the wheels 9 and this is accomplished by grasping one of the levers 18 and after releasing dogs 20 by pressure on the bell cranks 21, thereby 15 swinging rods 15 and through the intermeshing bevel gears 13 and 14 changing the position of wheels 9. This operation may be effected at either one side or the other of the machine, or at both, at the will of the 20 operator.

From Fig. 1, it will be seen that the beams 1 and 2 are disposed at an oblique angle to the line of travel of the machine which will cause the blades 7 to effectively 25 scrape the surface over which the apparatus is drawn.

From the foregoing description, taken in connection with the accompanying drawings, the advantages of the construction and 30 of the method of operation will be readily apparent to those skilled in the art to which the invention appertains and while I have described the principle of operation of the invention together with the device I now 35 consider to be the best embodiment thereof, I desire to have it understood that the device shown is merely illustrative and that such changes may be made as are within the scope of the claimed invention.

40 I claim:

1. In a machine of the class described, a pair of beams, cross bars connecting said beams, wheels having L-shaped axles jour-

naled on said beams and crossbars, bevel gears carried by said axles, longitudinally 45 alined rods having bevel gears mounted to mesh with the gears on said axles, levers fixed to said rods whereby said gears are actuated to change the position of said wheels, and means for locking said levers 50 in adjusted position.

2. In a machine of the class described, a pair of obliquely disposed parallel beams, cross bars connecting said beams, wheels having L-shaped axles journaled on said beams and cross bars, bevel gears carried by said axles, longitudinally alined rods carried by said cross bars and having bevel gears mounted to mesh with the gears on said axles, levers fixed to said rods whereby 55 60 said gears are actuated to change the position of said wheels, and means for locking said levers in adjusted position.

3. In a machine of the class described, a supporting structure including longitudinally spaced beams, cross bars connecting said beams, scraping blades depending from one of said beams, brackets projecting laterally and rearwardly from said beams, brackets projecting upwardly from said 65 70 cross bars in alinement with said beam carried brackets, L-shaped axles journaled in the brackets of said cross bars and beams, wheels carried by said axles, bevel gears mounted on said axles, rods mounted to turn 75 on said structure and having bevel gears meshing with the bevel gears of said axles, connected levers for operating said rods, and means for locking said levers in adjusted position.

In testimony whereof I affix my signature in presence of two witnesses.

EDWARD F. MITTENDORF.
